UNITED STATES PATENT OFFICE

116,330

DESIGN FOR A COMBINED FLOOR SCRUBBING AND POLISHING MACHINE

Rudolph A. Posch, near Lees Summit, Mo., assignor to Hillyard Chemical Company, St. Joseph, Mo.

Application March 30, 1939, Serial No. 83,922

Term of patent 14 years

To all whom it may concern:

Be it known that I, Rudolph A. Posch, a citizen of the United States, residing near Lees Summit, in the county of Jackson and State of Missouri, have invented a new, original, and ornamental Design for a Combined Floor Scrubbing and Polishing Machine, of which the following is a specification, reference being had to the accompanying drawing, forming part thereof.

Figure 1 is a front perspective view of the combined floor scrubbing and polishing machine showing my new design.

Figure 2 is a fragmentary top plan view thereof with the handle and electric cord portions shown broken away for convenience of illustration; and

Figure 3 is a fragmentary side elevational view of Figure 2.

I claim:

The ornamental design for a combined floor scrubbing and polishing machine, as shown.

RUDOLPH A. POSCH.
